CLAMP FOR DISPLAY PACKAGES

Morris Ladin, Brooklyn, N. Y., assignor to Economy Bias Binding Company, New York, N. Y.

Application April 8, 1932, Serial No. 604,055

3 Claims. (Cl. 24—81)

This invention relates to improvements in clamp devices for display packages and has more particular relation to improvements in packages for displaying colored tape, ribbon or other merchandise in connection with sewing thread of a matching shade or color.

The object of the invention is to provide a clamp that will fully display to the customer the texture and color of the tape, ribbon or the like in connection with a spool of silk or thread and to also protect not only the tape or ribbon but also the thread by a transparent and protecting covering such as "Cellophane."

One of the principal objects of the invention is to secure the tape upon a suitable base and then secure the spool or container for the silk or thread over the tape in such position that the color of the silk and the color of the tape will be in juxtaposition to show their similarity.

Another object of the invention is to provide a package of "Cellophane" wrapped tape and to attach or clamp a spool to the outside of this package without breaking the package "Cellophane."

Another object of the invention is to enclose both the package of tape and the spool in "Cellophane" and secure the two together by a detachable metallic fastening.

The invention also has other objects, all of which will be hereinafter more particularly set forth and claimed.

In the accompanying drawing forming part of this specification,

Figure 1 represents a perspective view of the package clamp embodying my invention.

Figure 2 represents a vertical section through the same on the line 2—2 of Figure 1.

Figure 3 represents a perspective view of a modified form of spool clamp, and

Figure 4 represents a detail perspective view of another modified form of spool clamp, the normal position of the spool tines being shown in dotted lines.

Described in general terms, the invention comprises a device or clamp for displaying binding tape or the like in connection with cotton or silk thread wound on a container such as a spool and mounted in juxtaposition to the tape, the tape and the spool both being covered by "Cellophane" so that the purchaser of the package can see the exact shade of the binding tape and also the exact shade of the thread on the spool without disarranging the wrappings of the package.

Described in detail, the binding tape or ribbon

specified quantities. This tape is secured in position against displacement by a printed folder 4 having advertising matter or trade-marks printed thereon in the space 5. This package is then covered by a "Cellophane" wrapping 2 which is suitably secured at the back of the package.

In order to securely hold the spool of thread in position on the front of the package and in juxtaposition to an exposed portion of the tape, I provide a wire holder or clamp 8. This holder, as best shewn in Figure 2, comprises two tines 10 having curved free ends 11 and 12 respectively. The tines 8 are intended to enter the aperture 12 of the spool from opposite ends and slide with the curved portions 11 and 12 against the inner wall of the aperture. The tines 10 form loops and are connected to an inwardly curved portion 9 adapted to lie at the back of the package and to constitute a friction retainer by pressing against the tape passing over the back of the package.

The normal position of the tines 10 is slightly outward so that when said tines are inserted in the opposite ends of the spool by springing, they will exert outward pressure against the inner walls of the passage in the spool and thus hold the spool firmly in position against displacement.

Further, the portion 9 of the holder is so forced into the back of the package against the binding tape as to prevent any possibility of the spool being accidentally displaced from the package.

The spool 7 is constructed of wood or other suitable material and the thread 6 thereon is protected by a "Cellophane" covering 6 secured thereabout and additionally held in position by the pressure of the spool against the front of the package under the tension of the tines 10.

It will be seen from the above description that while the silk or the thread is plainly visible, it is fully protected against air, dust or handling.

The location of the spool in relation to the tape is such that the color of the thread on the spool and the color of the tape is easily comparable and if desired the spool may be detached or attached by inserting the finger under the friction portion 9, drawing the same outward and sliding the spool and holder off the package or the opposite ends, or the tines 10 may be pulled outward out of the opening of the spool and thus disengage the spool and allow it to be removed from the package.

In the modified form of my invention shown in Figure 3, the tines 20—20 are somewhat similar to the tines 11 but are extended sufficiently to normally cross each other as shown so that when they are pulled apart and inserted into the spool, they will afford additional friction surfaces for

55 55

holding the spool in position. This holder 18 is provided with a portion 19 similar to the portion 9 of the first described holder for securing the holder in position on the package.

5 In the modified form of my invention shown in Figure 4, the tines 16 enter the spool aperture but normally extend diagonally upward as shown in dotted line so that they have to be pulled down to be inserted in the spool aperture. The normal position is shown at 17, dotted lines. These tines are bent back on themselves as at 14 to go under the card or display and the end of each tine is bent into an eye 15 that surrounds the companion tine so that the tines may be slid apart and pushed together with the ends 16 in the spool aperture. In pulling the tines 16 down so that they may be inserted in the spool aperture, tension is put upon the sliding eyes 15 so that after the tines are pushed together with the ends in the spool, they remain in this position because of this tension. If a spool is employed with a large central aperture, the positions of the tines 16 within the spool are similar to the form shown in Figures 2 and 3 in which the spool is centered by the 25 position of the tines.

It is contemplated to construct the wire holder of any spring wire or like material and to suitably plate or ornament the same, such for instance as chrome plating, to accentuate the beauty of the 30 package.

While I have described the spool holder or clamp as wire or metal it will be understood that any flexible material may be employed that has sufficient flexibility to spring the ends of the tines 35 into the spool and still have the loop hug the back of the package so that the spool will not slip off. Such material, for instance, as celluloid or the like may be employed. This, of course, would only include the main forms and does not contemplate 40 celluloid for the forms having the eyes 15.

It will be understood that if so desired the spool 7 may be of less diameter and extend entirely across the width of the package.

Having thus described my invention, what I claim as new and desire to secure by Letters Patent is:

1. A clamp device of the character described including in combination, a package engaging member in the form of a loop open at one side thereof, and having its closed side adapted to 10 extend across one side of a package and around the edges thereof, the open-ended side of the loop extending partially across the opposite side of the package and having portions projecting therefrom, and spool holding means on said projecting 15 portions adapted to centrally position a spool relative to said package.

2. A clamp device of the character described including in combination a package engaging member in the form of a loop open at one side 20 thereof and having its closed side adapted to extend across one side of a package and around the edges thereof, the open ended side of the loop extending partially across the opposite side of the package and having spool engaging and centering 25 portions and means for adjusting the width of the loop.

3. A clamp device of the character described including in combination a package engaging member in the form of a loop open at one side 30 thereof, and with a friction "hump" on its closed side and which is adapted to extend across one side of the package with the ends around the edges thereof, the open ended side of the loop 35 extending partially across the opposite side of the package and having portions projecting therefrom to enter the spool and formed to centre the spool upon the package.
